DESIGN FOR A STEERING WHEEL

John D. Villas, Minneapolis, Minn.

Application March 23, 1935, Serial No. 56,026

Term of patent 14 years

To all whom it may concern:

Be it known that I, John D. Villas, a citizen of the United States, residing at Minneapolis, in the county of Hennepin and State of Minnesota, have invented a new, original, and ornamental Design for Steering Wheels, of which the following is a specification, reference being had to the accompanying drawing, forming part thereof, and in which

Figure 1 is a top plan view of the steering wheel; and

Figure 2 is a side elevational view thereof.

Figure 3 is a detail sectional view on the line 3—3 of Figure 1.

The characteristic feature of the design is that the wheel is formed with the rim having a uniform cross section and U-shaped depressions at the spoke ends. Knobs are partially submerged in these depressions and are positioned at the ends of each spoke. The spoke ends are offset to merge with the aforementioned rim depressions.

I claim:

The ornamental design for a steering wheel, substantially as shown and described.

JOHN D. VILLAS.
